UNITED STATES PATENT OFFICE.

LOUIS HAAS, OF NEW YORK, N. Y.

CIGAR-BOX.

SPECIFICATION forming part of Letters Patent No. 363,064, dated May 17, 1887.

Application filed January 18, 1887. Serial No. 224,690. (No model.)

To all whom it may concern:

Be it known that I, LOUIS HAAS, of the city, county, and State of New York, have invented certain new and useful Improvements in Cigar-
5 Boxes, of which the following is a specification.

This invention relates to an improved cigar-
10 box by which the cigars are securely packed
in such a manner that they cannot be inter-
changed for cigars of inferior quality or of dif-
ferent manufacture, the cigars being packed at
the same time in the box in such a manner that a
neat and attractive advertisement for the manu-
15 facturer is produced; and the invention con-
sists of a cigar-box the end walls of which are
provided at or near their centers with slots,
through which bands, ribbons, cords, or other
devices are passed after the same have been
20 placed transversely over two or more layers
of cigars in the box the ends of said bands,
ribbons, &c., being pasted or otherwise re-
tained at the bottom of the box, and the slots
in the end walls closed by downwardly-bent
25 flanges of eyelets applied to said slots, so as to
prevent air from entering into the box.

In the accompanying drawings, Figure 1 re-
presents a top view of my improved cigar-box,
showing the band by which the cigars are re-
tained in the same. Fig. 2 is a vertical longi-
30 tudinal section on the line xx , Fig. 1; and Fig.
3 is an end elevation of the box.

Similar letters of reference indicate corre-
sponding parts.

In the drawings, A represents a cigar-box
35 of any suitable size, which is provided in the
middle parts of the end walls with slots a ,
said slots being provided with sheet-metal eye-
lets b , that are tightly applied by their flanges
to the end walls of the box. The layers of ci-
40 gars in the box are retained by longitudinal
bands, ribbons, or cords B, that extend trans-
versely across the bodies of the cigars, prefera-
bly at every second layer of the same, the ends

of each ribbon, band, or cord being passed
through the slots a to the outside, and se-
cured to the bottom by pasting, or in any other
suitable manner.

The eyelets b are provided at their outer
and upper edges with upwardly-extending
flanges of a sufficient width, so that they can be
bent downwardly over the openings or slots a
and close the same, while at the same time
binding tightly on the ribbons, bands, or cords
B, as shown in Fig. 2, whereby the evapora-
tion of moisture from the cigars in the box is
55 prevented.

The ribbons or bands B form a protecting
device for the cigars in the box, so that the
box cannot be refilled with cigars, nor cigars
of an inferior quality or of other manufacture
60 substituted. The bands or ribbons also form
a neat and attractive advertising device, on
which the special brand, trade-mark, &c., of
the manufacturer may be advantageously dis-
played.

Having thus described my invention, I claim
as new and desire to secure by Letters Patent—

The combination, with a cigar-box having
slots at the middle portion of its end walls, and
eyelets in said slots, said eyelets having flanges
70 at their upper and outer edges, of ribbons or
bands extending transversely over the layers
of cigars and through said eyelets to the bot-
tom of the box, to which they are attached, the
flanges of the eyelets being bent downward
75 over the bands or ribbons, so as to close the
slots in the end walls and bind firmly on the
bands or ribbons, substantially as described.

In testimony that I claim the foregoing as
my invention I have signed my name in pres-
80 ence of two subscribing witnesses.

LOUIS HAAS.
